UNITED STATES PATENT OFFICE.

HERBERT F. FREULER AND CHARLES L. MORRILL, OF BERKELEY, CALIFORNIA,
ASSIGNORS TO INTERSTATE FIBER COMPANY, LTD., OF HONOLULU, TERRITORY
OF HAWAII, A CORPORATION OF THE TERRITORY OF HAWAII.

DECORTICATING MACHINE.

1,427,201.

Specification of Letters Patent. Patented Aug. 29, 1922.

Application filed June 4, 1919. Serial No. 301,626.

To all whom it may concern:

Be it known that we, HERBERT F. FREULER and CHARLES L. MORRILL, citizens of the United States, residing at Berkeley, in the county of Alameda and State of California, have invented certain new and useful Improvements in Decorticating Machines, of which the following is a specification.

The present invention is a decorticating machine particularly designed for use in the treatment of *Musa sapientum* (banana stalks); however may be used in connection with *Musa textilis* (Manila hemp) or other similar fibrous stock of the endogen variety. The principal object of the invention is the production of a machine of the above character which will operate in an efficient manner in the treatment of the stock for which it is particularly designed and which possesses a simple and economical construction having great durability.

One of the principal features of the invention resides in the pulp-stripping mechanism which first acts upon the fibrous stock to sever the pulp therefrom and discharge it from the machine in a lacerated state. The fibrous portion of the stock is then passed through crushing rollers and thence to an outside scraping mechanism to remove the outer bark or cuticle covering the fiber. This scraping mechanism consists of a plurality of scraping knives mounted, preferably, on an endless chain in order that the knives will extend at right angles to the stock being treated thereby, and will move in a straight line during the scraping treatment or operation. From the outside scraping mechanism the fibrous stock passes to an inside scraping mechanism, consisting of a series of rotary knives. Feed rollers are provided for passing the fibrous stock from one mechanism to the other and are operated at substantially the same rate of speed. The scraping mechanisms above referred to are operated at a greater rate of speed than the feed rollers, thereby causing a strip of fibrous stock, which is being treated, to have its rear end portion, which is about to be passed from a mechanism, whipped around by the blades of the mechanism in order that the opposite face of the strip of fiber stock will be subjected at its tail or rear portion to the action of the scraping knives. The knives of the outside scraping mechanism

are yieldably mounted to have a sliding movement under pressure away from the stock and at right angles thereto, while the knives of the inner scraping mechanism are rigidly constructed and have no such yielding movement. This construction is designed to provide for varying conditions which arise in the treatment of the stock for which the machine is designed, and it is found that the best results are obtained by the construction shown.

The pulp-stripping mechanism is detachable from the rest of the machine, as occasion may arise where such mechanism is not needed.

The invention further resides in sundry details of construction, combination and arrangement of parts hereinafter more fully specified and defined in the specification.

In this specification and the annexed drawings, we disclose our invention in the form which we consider the best, but we do not limit our invention to such form because it may be embodied in other forms, and it is to be understood that in and by the claims following the description herein, we intend to cover our invention in whatever form it may be embodied.

Referring to the drawings:

Figure 1 is a side elevation of our invention with the driving gear removed.

Figure 2 is a front elevation of our invention.

Figure 3 is a cross sectional view on an enlarged scale of the pulp-stripping mechanism taken on line 3—3 of Figure 2.

Figure 4 is a side view of the spring guide plates of the mechanism.

Figure 5 is a rear view of one of said guide plates.

Figure 6 is a side view of the splitting knives of the stripping mechanism.

Figure 7 is a front view of part of the splitting knives of the stripping mechanism.

Figure 8 is a front view of the spring guide plates of the stripping mechanism and the channel bar on which said plates are mounted.

Figure 9 is a side view of the outside endless chain scraping mechanism for scraping the outside of the fibrous plant.

Figure 10 is a side view of a portion of the outside endless chain of said scraping mechanism.

- Figure 11 is a sectional view of one of the links of said chain with a knife spring mounted therein, forming one of the scraping units of said scraping mechanism.
- 5 Figure 12 is a plan view of one of the knives of said scraping mechanism and a link in which said knife is mounted.
- Figure 13 is a front view of one of the spring presser plates of said scraping mechanism.
- 10 Figure 14 is a side view of said presser plate and the spring mounting means therefor, said means being shown partly in section.
- 15 Figure 15 is a side view of one of the end disks of the drum scraping mechanism which scrapes the inside of the fibrous plant.
- Figure 16 is a plan of one of the slats which connect the end disks of the drum of 20 said drum scraping mechanism.
- Figure 17 is a view of the driving means of the drum of the inside scraping mechanism.
- 25 Figure 18 is a cross section of the drum and knives of the inside scraping mechanism taken on line 18—18 of Figure 20.
- Figure 19 is a plan of one of the knives of the drum scraping mechanism.
- 30 Figure 20 is a longitudinal section of the drum scraping mechanism taken on line 20—20 of Figure 1.
- Figure 21 is a side view of the presser means of the drum scraping mechanism for pressing the plant against the scraping 35 knives of said mechanism.
- Figure 22 is a rear view of the presser plate of said presser means.
- Figure 23 is a plan of the stripping knife blade.
- 40 Figure 24 is a side view of the driving gear at the left side of the machine.
- Figure 25 is a right side view of the gearing of the machine.
- 45 Figure 26 is a cross section of a stock of the stalk of a banana tree before it is treated by our machine.
- Figure 27 is a cross section of said stock after it has passed through the pulp-stripping mechanism.
- 50 Figure 28 is a cross section of the stock after its pulp has been stripped therefrom and its outside skin scraped by our machine.
- Figure 29 is a cross section of the fiber obtained from the stock after its pulp has been 55 removed therefrom, its outside skin scraped and the pulp on its inside scraped by our machine.
- Figure 30 is a side view of one of the outside tail scraper plates.
- 60 Figure 31 is a plan of said outside tail scraper plate.
- Figure 32 is an enlarged fragmentary face view of three of the inside scraping knives illustrating their edges.
- 65 In the drawings, 1 indicates a main frame including two side members 2 and 3 and connecting members 4, 5 and 6 which connect said side members together. The frame members 2 and 3 are mounted on runners 7. Each frame member includes a base 8 which rests upon and is secured to a runner 7, and uprights 9, 10 and 11 upstanding from said base. The connecting members 4 are threaded on their ends and extend through the side frame members 2 and 3 and nuts 12 70 screw on said threaded ends against said members whereby the ends of the connecting members are connected to the members 2 and 3. The connecting member 6 extends across the rear face of the uprights 9 of side members 2 and 3 and is bolted thereto by bolts 13. The member 5 has end flanges 14 which are bolted to the inside of uprights 10 of members 2 and 3 by bolts 15.
- 75 *Pulp-stripping mechanism.*—On top of the uprights 10 and 11 of the side frame members 2 and 3 rests side frames 16 and 17 respectively of the pulp-stripping mechanism. Each of said frames 16 and 17 includes a rear section 18 and a front section 19. Each of the section 18 has a base 20 which rests upon the uprights 10 and extends forwardly and rests upon the uprights 11 of the frame members 2 and 3. The section 18 is bolted to the uprights 10 by bolts 21, and the bases 20 thereof each has a lug 22 depending from its forward end into the upper end of the channel upright 11 of the frame members 2 and 3, respectively. Angle braces 23 are secured at one end to 100 the uprights 10 of frame members 2 and 3 by bolts 24 while their other ends extend between the forward wall of channel upright 11 and lug 22 (see Fig. 3). The frame section 19 rests upon the bases 20 105 of section 18 and has lugs 25 which depend over the forward edge of said bases and engage the front wall of the uprights 11 at the upper end of said uprights. The frame sections 18 and 19 are secured to the upper 110 ends of the uprights 11 by bolts 26 which extend through and bolt together the upper end of the front wall of said uprights, the upper ends of angle braces 23 and the lugs 22 and 25. The rear of the section 19 is 115 bolted to the upper forward portion of the section 18 by bolts 27. Feed rollers 30 and 31 are mounted in the forward part of frame section 19, the roller 30 being journaled at its ends in said frame section and the roller 31 being journaled at their ends in sliding blocks 32 slidably mounted in guides 33 in the upper forward part of the frame section 19. Top plates 34 are bolted to the top of guides 33 through which plates extend screws 35 from the blocks 32. Springs 36 surround the screws 35 between the blocks 32 and plate 34 and tend to force the roller 31 into contact with roller 30. Hand nuts 37 screw on the upper ends of 120 125 130

screws 35 against the plates 34 by means of which the roller 31 may be elevated slightly above the roller 31 against the tension of spring 36. A channel member 40 having 5 upstanding end flanges 41 provided with vertical slots 42 is adjustably secured to the frame section 19 by bolts 43 which extend through said slots. A pivot rod 45 is mounted in blocks 46 screwed to the lower wall 10 of channel 40 on which rod are pivotally mounted a plurality of spring guides 47, said guides having knuckles 48 through which said rod extends. The guides 47 are angular shaped having an upright member 15 49 on which are formed the knuckles 48, and a rearwardly extending member 50 over which the fibre passes from between the rollers 30 and 31. On the inner face of the intermediate wall of channel member 20 40 are studs 51 and on the rear face of the wall of the guide members 47 are studs 52 over which fit the ends of springs 53, interposed between said intermediate channel wall and said guide wall, which force the 25 guides forwardly until arrested by the engagement of lips 54, on the lower edges of the members 49 of the guides 47, with the underside of the lower wall of channel member 40 in which position the members 50 of 30 guides 47 are inclined upwardly in a rearward direction. Splitting knives 60 are secured at the rear of channel 40 to the intermediate wall thereof, said knives having upper horizontal cutting edges 61 which extend 35 rearwardly from the channel 40 to a point 62, see Fig. 6. A knife 65 is mounted upon the side frames of the section 19, slightly in rear of the splitting knives 60, for stripping the pulp from the plant, which 40 knife 65 includes a bracket 66 and a detachable blade 67 secured to the top of the bracket by screws 68. The bracket 66 has end flanges 69 provided with vertical slots 70 and is secured to the side frames of the 45 section 19 by bolts 71 extending through said slots, and the blade 67 has a forward horizontal edge 72 located above and to the rear of the points of the splitting knives 60. Above the knife 65 is a guide 75 extending between the frame sections 19 and secured to said section by screws 76 extending through flanges 77 on the ends of the guide. Below the stripping knife 65 and splitting knives 60, rollers 80 and 81 are 50 mounted in the lower forward part of frame section 19, the roller 80 being journaled at its ends in said section and the roller 81 being journaled at its ends in sliding blocks 82 slidably mounted in guides 83 in said section. Screws 84 in the section 19 extend 55 into the guides 83 and have disks 85 on their inner ends in said guides between which and the blocks 82 are interposed springs 86 which maintain the roller 81 under tension in contact with roller 80. The 60 frame section 19 and the parts mounted thereupon including the rollers 30 and 31, spring guide 50, knife 65, guide 75 and rollers 80 and 81, constitute a unit of the machine which may be termed a pulp-stripping 70 head, and may be removed from the machine by unscrewing bolts 26 and 27, particularly for the purpose of decorticating plants having no pulp or similar portions to be removed. Feed rollers 90 and 91 are 75 mounted in the rear frame section 18 of the side frames 16 and 17, the ends of roller 90 being journaled in said frame section 18 while the ends of the roller 91 are journaled in sliding blocks 92 slidably mounted 80 in guides 93 in said frame section. Plates 94 are bolted on top of the guides 93 and screws 95 extending through said plates into said guides have disks 96 on their inner ends in said guides between which and the blocks 85 92 are interposed springs 97 which maintain roller 91 under tension in contact with roller 90. A scraper 98 is pivotally mounted on the frame section 19 and is maintained in contact with roller 30 for scraping the 90 same by spring 99 connected at one end to the scraper and at the other end to one of said frame sections. Scrapers 100 and 101 are pivoted to the bases 20 of rear frame section 18 and are maintained in contact 95 with rollers 80 and 81 by springs 102 and 103 secured at one end respectively to said scrapers and at their other ends respectively to one of said bases and to the upper end of one of the uprights 11. Scrapers 104 100 and 105 are pivoted to the frame section 18 and are maintained in contact with rollers 90 and 91 by springs 106 and 107 secured respectively at one end to said scrapers and at their other ends to one of said 105 frame sections. A guide 108 pivoted at 109 to the uprights 11 extends downwardly and forwardly from the scraper 100.

Outside scraping mechanism.—To the rear upper part of the rear section 18 of the side frames 16 and 17 and to the rear of the uprights 10 of the frame members 2 and 3, are bolted the bases of triangular frames 110 and 111 by means of bolts 112 and 112', the apex of said frames extending rearwardly between and adjacent the uprights 9 of frame members 2 and 3. The frames 110 and 111 are properly spaced apart and held rigidly together, as a unit, by spacing bars 113 which are bolted at their ends to said frames. 115 A shaft 114 is journaled at its ends in the apex of the frames 110 and 111 and in the upper ends of uprights 9 of frame members 2 and 3, and on the outer ends of said shaft collars 115 are secured by set screws 116 120 which are adapted to bear against the uprights, thus holding the apex of the frames and the upper ends of said uprights rigidly together. A shaft 117 is journaled at its ends in the lower angle of the frames 110 130

and 111. A shaft 118 is journaled at its ends in sliding blocks 119 mounted in vertical guides 120 in the upper angle of frames 110 and 111. On the shafts 114, 117 and 118 inside and adjacent the frame 110 are respectively secured sprockets 121, 122 and 123 and inside and adjacent frame 111 respectively on said shafts are secured sprockets 124, 125 and 126. Chains 130 and 131 extend respectively over the sprockets 121, 122 and 123 and the sprockets 124, 125 and 126. Each of said chains includes links 132 and 133 (see Figs. 10, 11 and 12) pivoted to each other by pivot pins 134. The links 133 are formed with knife bearings 135 in which are reciprocatively mounted the ends of outwardly extending scraping knives 136, the ends of each knife being respectively mounted in the bearings of corresponding links 133 of chains 130 and 131. The knives 136 have outer scraping edges 136'. An opening 137 extends from the inner edge of each link 133 to the knife containing space in the bearing 135 thereof, in the inner end of which opening is screwed a plug 138. The inner edge of each knife 136 near the ends thereof is provided with notches 139 which register with the openings 137 in links 133, and in each end of each knife near its outer edge is formed a notch 140. A plate 141 extends across the outer end of the bearing 135 of each link 133 through said notch 140 in the end of the knife 136 mounted therein, the plate being secured to the bearing by screws 142. A spring 143 is interposed in each opening 137 of the links to engage in the notch 139 in the knife 136 and the plug 138, these springs urging the knives 136 outwardly until arrested by the engagement of the inner edges of the notches 140 with the plates 141. Extending inwardly from the frames 110 and 111 between sprockets 126 and 125, sprockets 125 and 124, and sprockets 124 and 126, are flanges 144, 145 and 146 to which backing plates 147, 148, and 149 are secured, by means to the outside of which are secured bearing plates 147, 148 and 149 by means of screws 150 against which plates bear the inner faces of the chains 130 and 131, see Fig. 9. To the bearing blocks 119 are secured screws 155 and 156 which extend upwardly through the upper walls 157 of the guides 120. Adjusting nuts 158 and 159, respectively, thread on the outer ends of said screws against said guide walls 157 for adjusting the blocks 119 vertically to vary the tautness of the chains 130 and 131. Lock nuts 160 and 161 screw on screws 155 and 156 against nuts 158 and 159 to lock said nuts to maintain the chains in adjusted position. A plurality of vertical spring presser plates 170 are arranged side by side between the frame members 2 and 3 and in front of the knives 136 on the forward reaches of chains 130 and 131, which extends between the sprockets 122 and 123 and the sprockets 125 and 126 respectively (see Figs. 1 and 9). Each presser plate 170 has a central vertical web 171 (see Figs. 13 and 14) on its forward face and a forked bearing 172 extending forwardly from said web, which bearing fits slidably on a web bearing support 173 extending forwardly from the frame member 5, whereby the presser plates are supported to reciprocate forwardly and 70 backwardly. Embossments 174 and 175 are formed on the web 171 below and above the bearing 172, and studs 176 and 177 extend rearwardly from said web and centrally with relation to said embossments respectively. 75 Set screws 178 and 179 extend forwardly through the frame connecting member 5 in alinement with the studs 176 and 177, respectively, and carry cups 178' and 179' on their forward ends to receive the rear ends 80 of springs 180 and 181, the forward ends of which respectively surround studs 176 and 177 and bear against the embossments 174 and 175. The rear faces of the presser plates 170 are formed with forwardly inclined lower and upper ends 182 and 183, respectively. From the lower ends of the presser plates 170 and slightly beyond the outer edges of the knives 136, extends a curved guide 185 which curves downwardly and rearwardly 90 around the outer edges of the knives in the links 133 engaging the sprockets 122 and 125. Brackets 190 and 191 are bolted by bolts 192 to the uprights 10 of frame members 2 and 3, respectively, and to the frames 100 110 and 111, respectively, by bolts 193, in which brackets are mounted feed and holder rollers 194 and 195, the ends of roller 194 being journaled in said brackets while the ends of roller 195 are journaled in sliding 105 blocks 196 slidably mounted in angular guides 197 on said brackets. Screws 198 extend through the outer end walls 199 of said guides carrying disks 200 within the guides between which and the blocks 196 are interposed springs 201 which maintain the roller 195 under tension in contact with roller 194. An inside tail scraper plate 202 is bolted, by bolts 203, to the lower rear edges of frames 110 and 111 tangentially from the 115 top of roller 195 and in slight pressing engagement with the outer edges of the knives 136 on the lower reaches of the chains 130 and 131, which extend between the sprockets 122 and 121 and sprockets 125 and 124, respectively. Scrapers 205 and 206 are pivoted on the brackets 190 and 191 and are held in scraping engagement with the rollers 194 and 195 below their point of contact by springs 207 and 208 which are secured at one 120 end to said scrapers and at their other ends to brackets. 125

Inside scraping mechanism.—Below the outside scraping mechanism just described, bearing frames 210 and 211 are bolted by 130

bolts 212 to the uprights 9 and 10 of the main frame members 2 and 3 respectively. In said frames are bearings 213 in which are journaled the ends of a shaft 214, extending 5 through a drum 215. On the heads 216 of the drum are annular collars or flanges 217 surrounding the shaft 214 and extending into and journaled in the hollow bearings 218 on the frames 210 and 211, the bearings 10 218 being eccentric to the bearings 213 also on said frame, thus journaling the shaft 214 and drum 215 eccentrically to each other. The drum heads 216 are connected by slats 219, (see Figs. 15, 18 and 20) the ends of 15 which fit in notches 220 arranged at a suitable distance apart in the periphery of the heads and are secured to the heads in said notches by screws 221. Secured to the shaft 214 near its ends, and interposed between the 20 latter and the drum journals 217, are drum drivers 222 and from the periphery at the outer ends of each of which extend two dogs 223 arranged diametrically opposite each other, which dogs are adapted to engage 25 arcuate lugs 224 on the outer ends of journals 217 to drive the drum when said shaft is rotated. Engaging plates 225 and 226 are respectively secured to the dogs 223 and the lugs 224 by screws 227 which plates take 30 the wear in the engagement of said dogs and lugs. The inner ends of the drives 222 are formed with annular flanges 228. The intermediate portion 229 of shaft 214 between the drives 222 is slightly larger than 35 the end portions of the shaft and is formed with longitudinal groove bearings 230 for scraping knives 231, the inner edges of which are formed with journals 232 which are maintained respectively in said bearings by 40 the engagement of flanges 228 with lugs 233 on the ends of said knives at their inner edges. Slotted knife guides 234 are arranged at the periphery of the drum heads 216, in which reciprocate flanges 235 projecting from the ends of knives 231 at their 45 outer edges, the slots 236 of said guides diverging to permit the knives to oscillate in their bearings 230 as the shaft 214 and drum 215 rotate eccentrically with relation 50 to each other, the knives being projected beyond and withdrawn within the periphery of the drum as the shaft and drum are so rotated as illustrated in Fig. 18. The knives 231 have outer scraping edges 237. At the 55 outer scraping edges of the knives 231 in the rear of the drum 215 are mounted side by side on frame connecting member 6 a plurality of concaved presser plates 240 (see Figs. 1, 2, 21 and 22). Each presser plate is 60 formed with a pair of rearwardly extending forked-shaped bearings 241 and 242 which fit loosely and slide on supporting lugs 243 and 244 respectively which project forwardly from frame connecting member 6. 65 On the rear face of said presser plates near

the lower and upper edge and in the center thereof are formed spring sockets 245 and 246, in which rest the forward ends of springs 247 and 248 respectively, the rear ends of which fit in cups 249 and 250 on the 70 forward ends of set screws 251 and 252, the screws 251 being mounted in and extending through a bracket 253 depending from the lower edge of frame connecting member 6 and the set screws 252 being mounted in 75 and extending through the upper part of said frame connecting member. The screws 252 and springs 248 are arranged so that the springs 248 bear horizontally against the upper portions of the presser plates 240 while 80 the set screws 251 and springs 247 are arranged so that the springs 247 bear against the lower rear portions of the presser plates radially toward the center of shaft 214, giving the maximum pressure of said springs 85 upon the lower portion of said presser plates toward the scraping edges of knives 231. The outermost presser plates 240 have outside flanges 255 which extend over the ends of the knives 231 and the drum 215 and prevent 90 the fiber strips passing between the knives and presser plates from working out sideways from the knives and drum. Frames 260 and 261 are bolted to the uprights 9 and 10 of the frame members 2 and 3 by bolts 95 262, in which frames are mounted feed rollers 263 and 264, the ends of roller 263 being journaled in said frames, while the ends of roller 264 are journaled in blocks 265, slidably mounted in guides 266 in said 100 frames. Set screws 267 extend through the end walls 268 of guides 266 and carry on their inner ends disks 269, between which and the blocks 265 are interposed springs 270 which urge roller 264 into contact with 105 roller 263. To angular brackets 271 on the rear of uprights 10, the ends of a frame member 272 are bolted by bolts 273, on which are slidably mounted side by side close to the edges of knives 231 a plurality of outside tail scraper plates 274 (see Figs. 1, 2, 30 and 31), said plates each including a slide member 275 provided with slots 276 through which extend bolts 277 screwing into the frame member 272, whereby the plates are 110 maintained in sliding position on said frame member. The frame member 272 has a forward upturned flange 278 in which are screwed a plurality of set screws 279, which carry disks 280 on their inner ends. Each slide member 275 has an upstanding lug 281, between which and each screw disk 280 is interposed a spring 282 which urge the scraper plates against the edges of knives 231. Set screws 283 extend through the 115 flange 278 and through lugs 284 upstanding from the slide member 275, and nuts 285 screw on the ends of said screws for engaging the lugs 284 for limiting the movement of the scraper plates toward the knives 231, 120 125 130

and for adjusting the limit of said movement. On the outside of the outermost scraper plates 274 are formed sockets 286 and on the inside of the frames 260 and 261 5 are formed sockets 287 in which sockets are interposed the ends of springs 288 which press the scraper plates close together and prevent any material from the fibrous plants from passing therebetween. Similar springs 10 289 and 290 are interposed between the uprights 10 and the outermost presser plates 170 and between the frames 260 and 261 and the outermost presser plates 240 whereby said plates are pressed together to prevent 15 any fibrous material from passing therebetween. A drum scraper 291 is pivotally mounted above the plates 274 and a rod 292 secured at its ends in the uprights 10 and is held in contact with the periphery of the 20 drum by spring 293 secured to the scraper and to upright 10. Scraper plates 294 and 295 are pivoted in the frames 260 and 261 and are held in contact with the lower surface of the rollers 263 and 264 respectively 25 by springs 296 and 297 connected at one end to arms 298 and 299 extending respectively from the scrapers and at their other ends to uprights 10 and 9 respectively.

Transmission.—A drive shaft 300 is journaled in bearings 301 bolted to the inside of uprights 9 of frame members 2 and 3. A pulley 302 is secured on the left end of said shaft to which power may be applied through a belt, not shown. On the right 30 end of drive shaft 300 is secured a sprocket 303 and on the right end of shaft 214 is secured a sprocket 304 over which sprockets extend a chain 305 by means of which the shaft 214 is driven from said drive shaft. A 35 sprocket 306 is also secured on the right end of shaft 214 and a sprocket 307 is secured on the right end journal of roller 90 over which sprockets extend a chain 308 whereby said roller is driven from the shaft 214. A 40 sprocket 309 is also secured on the right end of shaft 214 and a sprocket 310 is secured on the right end of a jack shaft 311 journaled in bearings 312 in the uprights 9 of frame members 2 and 3 over which sprockets 45 extend a chain 313 whereby said jack shaft is driven from shaft 214. A gear 314 is secured on the right end of said jack shaft and a gear 315 is secured on the right end of shaft 114 which meshes with gear 314 where- 50 by the shaft 114 and chains 130 and 131 are driven from the jack shaft 311, thus driving the outside scraping mechanism. A sprocket 316 is secured to the end of the shaft of the roller 19 (see Fig. 25), and a 55 sprocket 317 is secured on the shaft of the roller 30, over which sprockets extend a chain 318 whereby the roller 30 is driven from the roller 90. On the left end journals of rollers 90 and 91 are secured intermeshing gears 320 and 321 by means of which the 60 roller 91 is driven from the roller 90. On the left end journals of rollers 90, 194 and 263 are secured sprockets 322, 323 and 324 respectively, over which extend a chain 325 whereby the rollers 194 and 263 are driven 70 from the roller 90. An idler 326 is secured on the left end of shaft 117 over which travels chain 325 whereby the chain is maintained in effective driving engagement with sprocket 323. Intermeshing pinions 330 and 331 are secured on the left end journals of rollers 30 and 31, whereby the roller 31 is driven from the roller 30. Intermeshing pinions 320 and 333 are secured on the left end journals of rollers 90 and 80 whereby the 80 roller 80 is driven from the roller 90. A gear 334 is secured on the left end journal of roller 81 which meshes with gear 333 whereby the roller 81 is driven from the roller 80. Intermeshing pinions 335 and 336 are secured on the left end journals of rollers 194 and 195 whereby the roller 195 is driven from the roller 194. Intermeshing pinions 337 and 338 are secured on the left end journals of rollers 263 and 264 whereby the 90 roller 264 is driven from the roller 263.

The relative sizes of the rollers 90 and 91 and 30 and 31 and the sprockets 316 and 317 are such that the rollers 90 and 91 feed faster than the rollers 30 and 31 in order to 95 draw the fibrous strips taut between the rollers 90 and 91 and the rollers 30 and 31. The rollers 90 and 91, 194 and 195, and 263 and 264 are so geared through the medium of sprockets 322, 323 and 324 and chain 325 100 that they respectively feed the fibrous strips at the same rate of speed. The shafts 114 and 214 are so geared that the outside and inside scraping mechanisms travel faster than the feeding speed of feed rollers 90 and 105 91, 194 and 195 and 263 and 264.

Lubrication.—Oil cups 350 are mounted on the upper ends of tubes 351 which are secured in and extend through flanges 144 and plates 147. The links 133 are provided 110 with oil ducts 352 leading from their inner surfaces to the pivots 134 and the plugs 138 are provided with oil ducts 353 extending therethrough. Oil is delivered from the cups 350 through tubes 351 between the 115 chain bearing plates 144 and the inner surfaces of the chains 130 and 131, and then through ducts 352 and 353 to the pivots 134 and between the bearing surfaces of the knives 136 and guides 135, thus eliminating 120 the friction between said bearing plates and chains, between said pivots and the links 133 and between the bearing surfaces of said knives and guides.

An oil cup 360 is mounted in a bracket 361 125 secured to the frame 211, from which cup a tube 362 leads into a gland 363 fitted in one end of the shaft 214. The shaft 214 is formed with a central longitudinal bore 364 leading from the gland 363. Ducts 365 lead 130

from bore 364 to circular ducts 366 in the shaft 214 near the ends of bearing portion 229 and at suitable distances therebetween, the circular ducts 366 communicating with 5 the grooves 230 in said bearing portion. Oil passes from cup 360 through tube 362, gland 363, bore 364, ducts 365 and ducts 366 into the bearing grooves 230, thus oiling the knife bearings.

10 *Operation.*—The forward ends of strips of fibrous plants, such for example as shown in Fig. 26, are introduced side by side between the feed rollers 30 and 31 the inside downward. Said feed rollers feed the stock 15 forwardly over the spring guide 47 which guides the forward ends of the stock over the pulp-stripping knife 65 and under the guide 75 between the feed rollers 90 and 91. The feed rollers 90 and 91 being pressed together by springs 97 and the rollers 30 and 31 being adjusted slightly apart by nuts 37 and the rollers 90 and 91 traveling faster than the rollers 30 and 31, the fibrous stock 20 is drawn taut between the rollers 90, 91, 30 and 31 pressing down the spring guides 47 and drawn over the knife 65, the blade edge 72 of which cuts the pulp 370 (see Fig. 26) from the under side of the stock strips, close to the fiber 371 in said strips leaving the 25 strips as shown in Fig. 27. The pulp thus cut is guided downward by the knife frame 66 between the pulp discharge rollers 80 and 81, which draw the pulp taut over the splitting knives 60 causing it to be split into longitudinal shreds and deliver onto the chute 30 from which it drops into a basket (not shown) below the chute as a by-product. The feed rollers 90 and 91 feed the stock 30 with the pulp cut therefrom, as described, 40 into the outside scraping mechanism between the edges of knives 136 and the presser plates 170. The shaft 114, chains 130 and 131 and knives 136 traveling faster than the feed rollers, said feed rollers holding 45 said stock tightly between them, the edges 136' of the knives 136 scrape the outside skin or cuticle 372 off the stock leaving it as shown in Fig. 28. The knives 136 are maintained at right angles in contact with the 50 stock by the engagement of lugs 135' on the links 133 which hold the links of the chains straight, while traveling between sprockets and acting upon the stock. The forward ends of the stock are then guided by guide 55 185 between the feed rollers 194 and 195. When the tail ends of the stock strips pass from between and are released by the rollers 90 and 91, the scraper knives 136 traveling faster than the feed rollers 194 and 195, 60 carry the tails of the stock forward and whip them over said rollers onto the inside tail scraper plate 202 inside upward. The knives 136 passing over said scraper plate engage and scrape the remaining pulp 370 65 off the inside of the tails of the stock. The

feed rollers 194 and 195 feed the fibrous strips into the inside scraping mechanism between the knives 231 and the concaved presser plates 240. The drum 215 is rotated by the engagement of driver dogs 223 with 70 the lugs 224, the dogs and lugs being in such relation that continuous torque is applied to the drum thereby, while the knives 231 are carried around by the drum by the engagement of the slats 219 with the knives. The 75 dogs and lugs at one end of the drum are preferably arranged at ninety degrees to the dogs and lugs at the other end thereof. The shaft 214 and the knives 231 traveling faster than the feed rollers 194 and 195 the strips 80 of stock are drawn taut between the drum and the presser plates 240, said knives scraping the remaining pulp 370 off the inside of the strips, leaving only the fiber 371, as shown in Fig. 29, in their full length with 85 the exception of a piece of the outside skin 372 on the tails of the fiber sheets. From between the knives 231 and the presser plates 240 the strips pass between the feed rollers 263 and 264. When the strips have 90 passed from between the feed rollers 194 and 195, the knives 231 traveling faster than the feed rollers 263 and 264 and the fibrous strips, carry the tails of the strips forward and whip them around the rollers 263 and 95 264 upon the outside scraper plates 274 with the outside of the stock strip facing upwardly or contiguous to the drum 215. The knives 231 passing over said plates scrape the skin 272 off the outside face of the tail 100 ends of the fibrous strips. The feed rollers 263 and 264 feed the remaining fiber strips 271 forward and deposit them below.

A cleaner 380 is provided for cleaning the pulp from the knives 136 after they have 105 scraped said strips. Said cleaner includes two pulleys 381 and 382 journaled in brackets 383 on the rear of the frames 110 and 111, and a belt 384 traveling over said pulleys, with blades 385 projecting from said belt at such 110 intervals that they are engaged by the forward faces of the knives projecting from the upper rear reaches of the chains 130 and 131 between the sprockets 121 and 123 and the sprockets 124 and 126 and are moved upwardly carrying the belt around the pulleys. The pulleys 381 and 382 are journaled at 115 such distances from the chains that they are engaged by the forward faces of the knives at the pulley 381 and gradually withdraw 120 outwardly over said faces and escape the same at the pulley 382 as the blades and belt are moved around the pulleys, thus wiping and cleaning the pulp from the knives.

Any fiber that may break off between the 125 knives 136 is discharged therefrom by the spreading of the knives around the sprockets 121 and 124 and by the centrifugal action of said knives.

The eccentric movement of the drum 215 130

and shaft 214 causes the knives 231 to project outwardly from the periphery of the drum when adjacent the presser plates 240 to scrape the pulp off the inside of the fibrous strips, and to withdraw within the periphery of the drum after passing beyond the presser plates 274, depositing the pulp clinging thereto upon the periphery of the drum, from which the pulp is scraped off by the scraper 291, thus cleaning the knives and the drum for their next operation.

The edges of alternate knives 231 are straight and serrated, and the serrations of each serrated blade are staggered with regard to the serrations of the next serrated blades, as shown in Fig. 32. The serrations served to comb the material covering the fiber while the straight edges of the next blades scrape the combed material from the fiber, thus most effectively removing the material from the fiber.

The slats 219 are of steel with hardened edges which form hard bearing surfaces for the knives 231. The slats may be removed when worn, by unscrewing the screws 221, and new slats screwed to the drum heads in place thereof.

The inner ends of the slots 236 are inclined outwardly toward the axis of the drum 215 so that any material that falls in said slots will be directed by said inclined ends outwardly from the drum, thus preventing the material from falling within and choking up the drum.

35 A platform 400 may be mounted on the forward part of the machine upon which the operator may stand.

The machine being mounted on runners 7 may be drawn over the ground from place to place for convenience of operation of the machine.

Having described our invention we claim as new and wish to secure by Letters Patent:

1. A decorticating machine comprising means for preliminarily removing the pulp from strips of fibrous stock; means for subsequently scraping the outer cuticle and pulp from the stock, said means including traveling knives and yieldably mounted pressure plates, between which said stock is fed, said knives being yieldably mounted; and means for finally removing the pulp from the inside face of the stock, said means including a plurality of rigidly mounted and moving knives.

2. A decorticating machine comprising mechanism for preliminarily cutting pulp from strips of fibrous stock; means for scraping the outer cuticle and pulp from the stock comprising a traveling belt having yieldably mounted scraping knives and pressure plates arranged opposite to said knives and between which the fibrous stock passes; and a mechanism for scraping the pulp from the inner face of the stock comprising rigid-

ly mounted and revolving knives, and pressure plates arranged opposite said knives, between which said stock passes.

3. A decorticating machine comprising mechanism for removing pulp from fibrous stock in strips; means for subsequently acting upon the stock comprising a traveling belt and pressure plates between which the stock is passed, said belt having a plurality of scraping knives thereon mounted to yield under pressure in a direction at substantially right angles relatively to the stock; and means for finally acting upon the stock comprising a rotating drum and pressure plates opposing the drum between which the stock passes, said drum having a plurality of rigid knives thereon.

4. A decorticating machine comprising mechanism for removing pulp from fibrous stock in strips; means for subsequently acting upon the stock including a plurality of scraping knives mounted to travel in a straight line while acting upon the stock, pressure plates opposing said knives and between which the stock passes; and means for finally acting upon the stock including rotating scraping knives and pressure plates opposing said knives.

5. A decorticating machine comprising mechanism for removing pulp from fibrous stock in strips; means for subsequently acting upon the stock including a plurality of scraping knives mounted to travel in a straight line while acting upon the stock and yieldably mounted pressure plates opposing said knives between which the stock passes, said knives being yieldably mounted to move in a direction at right angles to the stock under pressure; and means for finally acting upon the stock including rigidly mounted rotating knives and pressure plates opposing said knives between which the stock passes.

6. A decorticating machine comprising mechanism for acting upon the stock including a plurality of scraping knives mounted to travel in a straight line while acting upon the stock, pressure plates opposing said knives and between which the stock passes; and means for subsequently acting upon the stock including rotating knives and pressure plates opposing said knives between which the stock passes.

7. A decorticating machine comprising means for acting upon the stock including a plurality of scraping knives mounted to travel in a straight line while acting upon the stock and yieldably mounted pressure plates opposing said knives between which the stock passes, said knives being yieldably mounted to move under pressure in a direction at substantially right angles to the stock; and other means for acting on the stock including rigidly mounted rotating knives and pressure plates opposing said knives between which the stock passes.

8. A decorticating machine comprising two sets of feeding means, a mechanism interposed between said sets of feeding means including a plurality of scraping knives 5 mounted to travel in a straight line while acting upon fibrous stock, pressure plates opposing the knives and one arranged after each set of feeding means, the second set of feeding means acting to discharge the stock, 10 a second mechanism for acting upon the stock including rotary scraping knives and adapted to receive the stock discharge from said second set of feeding means, a third feeding means positioned to discharge the 15 stock from said second mechanism, pressure plates arranged to oppose the rotating knives of said second mechanism, one positioned on each side of said third feeding means, means for actuating said feeding 20 means at substantially the same rate of speed and for actuating said scraping mechanisms at a greater rate of speed, whereby each mechanism is caused to act upon the forward end of one surface of the 25 stock and the rear end of the other surface of the stock.

9. A decorticating machine and outside scraping mechanism to act upon the outer face of fibrous stock, and inside scraping 30 mechanism adapted to act upon the inner face of fibrous stock; said outside scraping mechanism including feed rollers and discharge rollers for drawing the stock to the mechanism, moving scraping knives to 35 travel in a straight line while acting upon the stock and interposed between said feed and discharge rollers, a pressure plate arranged between said rollers and another pressure plate arranged beyond the discharge roller, said plates opposing said knives; the inside scraping mechanism being adapted to receive the stock from said discharge rollers and comprising a plurality of rotatable knives, rolls for discharging 40 the stock from said inside scraping mechanism and pressure plates opposing said rotatable knives and arranged on each side of said last mentioned discharge rolls; and means for actuating the feed and discharge 45 rollers at substantially the same rate of speed and for actuating said mechanism at a greater rate of speed whereby each mechanism is caused to act upon the forward end of the stock on one face and the rear end 50 portion of the stock on its other face.

10. A decorticating machine comprising a mechanism for scraping the outside face of fibrous stock, including traveling knives which move in a straight line when acting 55 upon the stock, feeding and discharge rollers positioned relatively to said knives for moving the stock through said mechanism at one rate of speed, a scraper surface opposite said knives with which the latter co- 60 operate when acting upon the stock, said

knives being adapted to move at a greater rate of speed than said rollers, another scraping surface positioned beyond the discharge rollers, whereby the tail portion of the inner face of the stock will be acted on 70 by said knives; and inside scraping mechanism for the stock including rotary knives adapted to receive the stock from said discharge rollers, a set of discharge rollers for said inside scraping mechanism, scraping surfaces to cooperate with said rotary knives one arranged on each side of said last-mentioned discharge rollers, said latter discharge rollers operating at a slower speed than said rotary knives, whereby the 80 tail portion of the outer surface of the stock is operated upon.

11. In a machine of the character described, a pair of feed rollers, a second pair of feed rollers to grip fibrous stock tighter 85 than the first pair of feed rollers, pulp stripping means including knives interposed between said first and second pair of rollers, means for rotating said second feed rollers faster than said first feed rollers to draw 90 the stock taut between said pairs of rollers and over said stripping means, whereby the pulp is severed from the stock, and a pair of discharge rollers below said knives for discharging the pulp as it is severed from 95 the stock.

12. In a machine of the character described, a pair of feed rollers, a second pair of feed rollers to grip fibrous stock tighter than the first feed roller, pulp stripping 100 means interposed between said first and second pairs of rollers, a guide interposed between said first feed rollers and the stripping means for guiding the stock over the latter to said second rollers, and means for 105 rotating the second pair of feed rollers faster than the first pair of feed rollers to draw the stock taut between said pairs of rollers and over said stripping means, so that the pulp will be severed from the stock 110 said guide yielding under the pressure of said stock thereagainst.

13. In a machine of the character described, a pair of feed rollers, a second pair of feed rollers to grip fibrous stock tighter 115 than said first feed rollers, pulp-stripping means interposed between said first and second pairs of feed rollers, a plurality of yieldable guides independently mounted side by side between said first feed rollers and said stripping means for guiding the stock over the latter to said second rollers, and means for rotating said second feed rollers faster than said first feed rollers to draw 120 the stock taut between said pairs of rollers and over said stripping means, whereby the pulp is severed from the stock said guides yielding independently under the pressure of the stock thereagainst.

14. In a machine of the character de- 130

- scribed, a pair of feed rollers, a second pair of feed rollers to grip fibrous stock tighter than the first rollers, pulp stripping means interposed between said pairs of rollers, a 5 spring guide interposed between the first rollers and said stripping means for guiding the stock over the latter to said second rollers, and means for rotating said second feed rollers faster than said first feed rollers
- 10 to draw the stock taut between said pairs of rollers and over said stripping means whereby the pulp is severed from the stock, said spring guide yielding under the pressure of the stock thereagainst, and means for adjusting said guide with relation to the line 15 of feed between said pairs of feed rollers.
15. In a machine of the character described, two pairs of feed rollers, the second of said pairs being adapted to grip fibrous 20 stock tighter than the first pair, pulp stripping means interposed between said pairs of rollers, means for rotating the second pair of rollers faster than the first pair to draw the stock taut therebetween and over 25 said stripping means, pulp discharging means whereby the pulp is severed from the stock including a guide arranged to direct the pulp from the stock into said discharge means.
- 30 16. In a machine of the character described, pulp stripping means including a frame and an adjustable and normally stationary blade secured to said frame, and means for feeding fibrous stock over said 35 blade to cut the pulp in strips from the stock.
17. In a machine of the character described, pulp-stripping means including a frame and a cutting blade secured to the 40 frame, and means for feeding fibrous stock over said blade to cut the pulp in strips from the stock, and a pulp discharging means, said knife frame having means arranged to guide the pulp as it is cut from 45 the stock into said discharge means.
18. A machine for decorticating fibrous stock, including in combination, means for removing pulp from the stock, a plurality of splitting knives spaced apart and arranged 50 below said pulp-removing means, and means for drawing said pulp so removed from the stock over said splitting knives, whereby the pulp is lacerated.
- 55 19. The combination with a machine for removing the cuticle and cutis from fibrous stock including a pair of feed rollers, of a removable attachment for said machine comprising a pair of feed rollers arranged in advance of said first-mentioned feed rollers, means between said pairs of feed rollers over which the fibrous stock is drawn by 60 said second feed rollers for removing the pulp from said stock.
20. The combination with a machine for removing the cuticle and cutis from fibrous stock, including a pair of feed rollers, of an attachment for said machine comprising a pair of feed rollers arranged in advance of the first mentioned feed rollers, pulp-stripping means interposed between said first and 70 second feed rollers and over which the stock is drawn, means for splitting the pulp after being stripped from said stock.
21. In a decorticating machine, a pair of feed rollers a second pair of feed rollers, 75 means interposed between said feed rollers for removing pulp from fibrous stock, means for discharging the pulp from the machine, said first-feed rollers, pulp-removing means and discharge means being detachable from 80 the machine.
22. In a decorticating machine, a scraping mechanism, including a series of scraping knives mounted to move in a straight line while acting upon fibrous stock, and a relatively stationary scraping surface opposing the knives and to cooperate therewith during the scraping operation, and means for preventing flexure of said series of knives away from the scraping surface under pressure of the stock. 85
23. In a decorticating machine, a scraping mechanism including a traveling carrier having a series of knives mounted to move in a straight line while acting upon fibrous stock, and a relatively stationary scraping surface opposing said knives to cooperate therewith during the scraping operation, and means for preventing flexure of said carrier away from the scraping surface under pressure of the stock, said knives being yieldable in the carrier and under pressure of the stock in a direction substantially at right angles relatively to the stock being treated. 90
- 105
24. In a decorticating machine, a scraping mechanism including a traveling carrier having a series of knives mounted to move in a straight line while acting upon fibrous stock, and yieldably mounted scraping surface opposing said knives and relatively stationary thereto to cooperate with said knives during the scraping operation, and means for preventing flexure of said carrier away from the scraping surface under pressure of the stock said knives also being yieldable under pressure in a direction substantially at right angles relatively to the stock being treated. 110
- 115
25. In a decorticating machine, a scraping mechanism including a plurality of blades mounted to travel substantially in a straight line in a non-flexible series while acting upon fibrous stock, and a plurality of yieldable pressure plates independently mounted side by side and opposing said knives, and means for feeding the fibrous stock between said knives and pressure plates. 120
- 125

26. In a decorticating machine, a scraping mechanism including a pair of endless belts, spaced from each other, a plurality of transversely arranged knives extending between the belts and mounted thereon, bearing plates over which said belts travel, and yieldable pressure plate opposing said knives.

27. In a decorticating machine, a scraping mechanism including a pair of endless chains spaced from each other, a plurality of transversely arranged knives extending between the belt and mounted thereon, and abutting means between the links of the chains for limiting the flexure of the chains in a backwardly direction, and yieldably mounted pressure plates opposing said knives.

28. In a decorticating machine, a scraping mechanism including a chain, a bearing plate over which said chain travels, knives mounted on the links of the chain, yieldable pressure means opposing said knives and between which knives and pressure means the fiber stock is fed, and abutting means between links of the chain for limiting flexure thereof in a direction away from said pressure plates, whereby the knives are maintained at right angles to the stock while acting thereon.

29. In a decorticating machine, a chain, knives mounted on said chain, pressure means opposite said chains between which knives and pressure means a strip of fibrous stock is fed, a belt arranged adjacent one reach of said chain, and blades on the belt to engage the forward faces of the knives to wipe the latter outwardly as they travel forwardly with the knives.

30. A decorticating machine including sprockets, chains passing over said sprockets, scraper knives on the chain, pressure means opposite the knives of one reach of the chain, means for feeding a fibrous stock between said knives and presser means, means beyond one reach of said chain for feeding the stock therefrom, both of said feeding means feeding the stock in the same direction but at a slower speed than said chain, and a tail scraper plate opposite said knives of the next reach of said chain upon which said knives scrape the tail ends of the stock.

31. In a decorticating machine, three sprockets, a chain traveling over said sprocket, paper knives on said chain, presser means opposite the knives on one reach of the chain, means for feeding fibrous stock between the knives of said chain reach and said presser means, means beyond said chain reach for feeding the stock therefrom, both of said feeding means feeding in the same direction but at a lower rate of speed than the movement of the chain, and a tail scraper plate opposite the next reach of the sprocket

upon which the knives scrape the tail ends of said stock.

32. In a decorticating machine, a chain, a bearing plate over which said chain travels, spring-pressed knives, slidably mounted in said chain, relatively stationary and yieldable presser means opposite said knives between which knives and means a strip of fibrous stock is fed.

33. In a decorticating machine, a scraping mechanism including a chain, scraping knives slidably mounted in said chain, removable plugs closing openings in the inner face of said chain, springs interposed in the openings between said plugs and said knives for urging the latter outward, means for limiting the outward movement of said knives and means for feeding and holding fibrous stock in scraping relation to the edges of said knives.

34. In a decorticating machine, a scraping mechanism including a chain, scraping blades slidably mounted on the outer faces of the links of the chain to have a movement substantially at right angles to the movement of the chain, the links of the chain carrying said blades having bores therein, plugs removably secured in the inner ends of said bores, springs in said bores and interposed between said plugs and said knives for urging the latter outwardly, means for limiting the outward movement of the knives, and means for feeding and holding fibrous stock in scraping relation to the edges of said knives.

35. In a decorticating machine, a scraping mechanism including a chain, scraping knives slidably mounted in links of the chain, springs in the links of the chain urging said knives outwardly from the chain, said knives having notches in their end portions, plates extending through said notches and detachably secured to said links respectively, for limiting the outward movement of the knives, and means for holding and feeding fibrous stock in scraping relation to said knives.

36. In a decorticating machine, a scraping mechanism including a pair of chains spaced from each other, a plurality of transversely arranged knives extending between said chains and slidably mounted on links thereof, means for normally urging said knives outwardly from the chains, the ends of said knives having notches therein, and detachable keeper plates secured to said links of the chain and engaging in said notches to limit the outward movement of said knives, and means for feeding and holding fibrous stock in scraping relation to said knives.

37. In a decorticating machine, a shaft having radially arranged knives thereon, a drum eccentrically mounted about the shaft and through which said knives are extended

and retracted when said shaft and drum are rotated, concave presser plate arranged adjacent the drum to cooperate with the knives when they are extended from the drum, adjustment members, springs interposed between said plate and adjustment members, one of said adjustment members being arranged to extend radially with respect to the center of the shaft and the other adjustment member being arranged to extend at substantially a tangent relatively to the drum.

38. In a decorticating machine, a shaft, having radially extending knives thereon, a drum eccentrically mounted about the shaft and through which said knives are extended and retracted when said shaft and drum are rotated, a concave presser plate arranged adjacent the drum to cooperate with the knives when the latter are projected from the drum, adjustment members, springs interposed between the adjustment members and said plate for yieldably mounting the latter, one of said adjustment members being arranged adjacent the feed end of the plate and extending substantially at a tangent relatively to the drum, and the other of said adjustment members and springs being arranged adjacent the discharge end of the plate and extending radially with respect to the center of the shaft.

39. In a decorticating machine, a shaft having radially extending knives thereon, drum heads arranged eccentrically about the shaft and concentric with each other, said drum heads having radial slots in their peripheries the walls of which slots diverge inwardly for a distance, said slots receiving lateral projections on the ends of said knives, and keeper strips extending longitudinally of the drum and interposed between said knives and detachably secured to the peripheries of said drum.

40. In a decorticating machine, a shaft having radial blades extending therefrom, a drum mounted eccentrically about the shaft and through which said blades are projected and retracted, presser plates adapted to cooperate with the drum when the knives are extended, means for feeding fibrous stock between said plate and drum at a speed less than the speed of the drum, means for discharging the stock at the end of said plate at the same rate of speed as said feeding means, and a plurality of yieldable presser plates mounted beyond said discharge means to cooperate with the knives of the drum before they are retracted within the latter, whereby the tails of the stock strips are whipped around by the

movement of the drum upon said latter plates and scraped by said knives.

41. In a decorticating machine, a drum having a plurality of scraping knives which are projected and retracted within the drum, presser plates adapted to cooperate with the knives when extended from the drum, means for feeding fibrous stock between said plates and knives at a rate of speed less than that of the drum, means for discharging stock from said plate at the same rate of speed as the feeding means, a plurality of spring-pressed presser plates mounted side by side beyond said discharging means and adapted to cooperate with the projected knives, whereby the stock are moved around upon said last-mentioned presser plate and the tail ends thereof scraped by said knives.

42. In a decorticating machine, a drum having a plurality of scraping knives adapted to be projected therefrom and retracted therein during the rotation of the drum, a presser plate adapted to cooperate with the knives when extended, a plurality of second presser plates arranged beyond said first presser plate and mounted side by side to cooperate with the knives while projected, means for feeding fibrous stock between the knives and the first presser plate, and means for discharging said stock from the drum and arranged between said first and second presser plate, the speed of said feeding and discharge means being less than that of the drum, whereby the stock is moved around upon said last-mentioned presser plate and the tail ends thereof scraped by said knives, and means for adjustably limiting the pressing movement of each of said second presser plates.

43. In a decorticating machine, a scraping mechanism including scraping knives, a plurality of presser plates mounted side by side adjacent said scraping knives, means for feeding and holding fibrous stock between said knives and said scraper plates to scrape said stock, and means for pressing said presser plates inwardly toward each other.

44. In a decorticating machine, a scraping mechanism including scraping knives, a plurality of presser plates mounted side by side adjacent said scraping knives, means for feeding and holding fibrous stock between said knives and said presser plates to scrape the stock, means for operating said feeding means slower than said scraping knives.

In testimony whereof we affix our signatures.

HERBERT F. FREULER.
